CLAIM

The ornamental design for an on-body injector for drug delivery, as shown and described.

DESCRIPTION

FIG. 1 is a perspective view showing a new design for an on-body injector for drug delivery;

FIG. 2 is a top view of the on-body injector for drug delivery of FIG. 1;

FIG. 3 is a bottom view of the on-body injector for drug delivery of FIG. 1;

FIG. 4 is a right-side view of the on-body injector for drug delivery of FIG. 1;

FIG. 5 is a left-side view of the on-body injector for drug delivery of FIG. 1;

FIG. 6 is a back view of the on-body injector for drug delivery of FIG. 1; and,

FIG. 7 is a front view of the on-body injector for drug delivery of FIG. 1.

(Continued)

The dashed lines showing portions of the on-body injector for drug delivery are included for the purpose of illustrating environment and form no part of the claimed design.
